Application December 30, 1947, Serial No. 794,618

4 Claims. (Cl. 49—7)

1

This invention relates to electric gaseous discharge devices and more particularly to fluorescent lamps of the curved or circular type.

An object of this invention is to provide apparatus for accurately forming a substantially circular glass tube.

Another object of this invention is to provide apparatus for accurately forming a substantially circular fluorescent lamp from a helically formed section of glass tubing.

A further object is to provide apparatus for accurately forming a substantially circular fluorescent lamp from a helically formed section of glass tubing which has had its inner wall coated with a luminescent material and electrodes sealed in the ends thereof.

Other objects advantages and features will be apparent from the following description when read in conjunction with the accompanying drawings in which:

Figure 1 is a top plan view of one modification of the apparatus of my invention;

Figure 2 is a front elevational view of the apparatus shown in Figure 1;

Figure 3 is a side elevational view of the apparatus shown in Figure 1;

Figure 4 is a fragmentary detail plan view showing the manner in which one of the lamp lead wires is secured to the base of the apparatus;

Figure 5 is a front perspective view of another modification of the apparatus of my invention;

Figure 6 is an enlarged perspective view of that portion of the apparatus of Figure 5 which accomplishes the formation of a circular glass tube from a length of helically formed glass tubing; and

Figure 7 is a front elevational view of the apparatus of Figure 5.

This invention embodies the idea of providing a flattening jig whereby a length of helically formed glass tubing, which has had its inner wall coated with a luminescent material and electrodes sealed at each end thereof, may be formed into a circular lamp.

The manufacturing of a circular fluorescent lamp presents many problems which are not confronted in the manufacturing of conventional linear type lamps. It is quite difficult to start with a curved tube of the exact dimension and configuration finally desired because of the difficulties which would be encountered in coating the inner wall of the tube with luminescent material and sealing electrodes in the ends thereof. This would be so because the ends of the tube would be quite close to each other and in the

2

same horizontal plane. Thus, far too little working area about the ends of the tube would be available for accomplishing these operations.

Basically there are, in general, two sequences of manufacturing operations possible. One may start with a conventional linear tube, coat it with luminescent material, seal electrodes in the ends thereof, and then bend the tube to the desired form, or one may start with a helix of several turns of tubing, cut it into several units of about one turn each, coat each unit with a luminescent material, seal the electrodes in the ends thereof and then form the tube into the finally desired shape. In both cases the lamp is evacuated, a filling of inert gas is introduced therein, and the exhaust tube sealed, after the tube has been fashioned to the finally desired form.

The apparatus of this invention provides means whereby a helically formed unit of glass tubing which has had its inner wall coated with luminescent material and electrodes sealed at each end thereof may be shaped into its final circular form prior to evacuation.

The unit on which this operation is performed is formed from single turn sections cut from a helix of glass tubing, with a space between the ends thereof preferably slightly less than the finally required spacing. The pitch of the helix is predetermined so that the ends of each unit cut therefrom will be offset from each other the desired amount. Although this helically formed unit of glass tubing may be obtained by making a simple radial cut at the desired point on the helix, we have found it more desirable to cut the tubing so that the end faces of the unit of tubing cut are substantially parallel to a plane containing the axis of the helix and passing through the center of the space between the ends so cut. The inner wall of each unit is coated with luminescent material and electrode mounts are sealed in each end thereof, at least one of said mounts being provided with an exhaust tube through which the sealed device may be evacuated. This exhaust tube is then bent at right angles and perpendicular to the axis of the helix at a point along its longitudinal axis where it is disposed outside the re-entrant stem of the electrode mount. This is done to permit the positioning of the lamp in the flattening jig.

We have found it desirable to position this helically formed unit of glass tubing on the flattening jig with reference to a line running through the center of the circle defined by the unit and through the center of the space between the ends of the unit as finally formed.

Referring now to the drawings, and more particularly to the embodiment illustrated in Figures 1, 2, 3 and 4, the flattening jig comprises a base plate 1 on which a lamp (the unit or section of tubing referred to above) 2, is positioned, an adjustable yoke 3, a fixed stop 4, and an adjustable eccentric stop 5, all of which are mounted on the base plate and which serve as guides in positioning the lamp 2 on the base plate, a clamping arm 6 pivotally mounted on the eccentric stop 5 for holding the lamp 2 in position during the flattening operation, and a pair of pivotally mounted arms 7 and 8 provided with ceramic V-blocks 9 and 10 respectively on their free ends, the V-block 9 engaging the lamp 2 adjacent to the end 11 thereof, and the V-block 10 engaging the lamp adjacent to the end 12 thereof. The arm 7 is pivotally mounted on the block 14 and the arm 8 is pivotally mounted in the plate 15. The arm 8 is mounted in a manner which will permit a small amount of horizontal angular movement thereof, the purpose for which will be described later.

In operation, the lamp 2 is placed on the base plate 1 with the end 11 thereof abutting the stop 4, and the exhaust tubulation 31 resting on or slightly above the upper surface of the stop 4. One of the lead-wires 33 may then be wound about a stud 32 on the base plate 2 (Figure 4). Although this is not necessary, it has been found desirable because it aids in securing this end of the lamp in position. The other lead-wire should be bent outwardly substantially as shown in Figure 4 so that it will not interfere with the operation of the jig.

The arm 7 is then moved into position by causing the V-block 9 to engage the lamp 2 adjacent the end 11 thereof. The V-block 9 is provided with a cam 20, the outer surface of which engages the end 11 of the lamp.

The adjustable yoke 3 which is mounted on the base plate 1 serves as an internal centering gauge and is a means for centering the lamp 2 on the base plate so that the center of the circle defined by the lamp is on a line passing through the center of the space between the ends of the lamp. The position of the lamp 2 on the base plate 1 is adjusted so that both of the arms 13 of the yoke 3 touch the lamp. These two points of contact, in conjunction with the disposition of the end 11 of the lamp in contact with the stop 4, provide a three-point contact for positioning the lamp. Although we have found the use of the adjustable yoke to be of assistance in accurately positioning the lamp 2 for the flattening operation we have also found that its use may be dispensed with and the lamp lined up visually if desired.

The eccentric stop 5 is then rotated until it touches the lamp 2. The clamping arm 6 is then moved into position to lock the lamp 2 to the base plate 1 (Figure 1). The adjustable yoke 3, if used, may then be removed from the jig. The lamp 2 is now held in position on the jig by the stop 4, the V-block 9, the eccentric stop 5 and the clamping arm 6.

As mentioned above each of the arms 7 and 8 have a weighted V-block 9 and 10 respectively disposed on its free end. The V-block 9 is provided with a cam 20 and the V-block 10 is provided with a cam follower 21. The cam and its follower are provided to insure an accurate predetermined spacing between the ends 11 and 12 of the lamp 2 at the end of the flattening operation.

As mentioned above, the arm 8 is pivotally mounted in the plate 15 in a manner which will permit a small amount of horizontal angular movement. This is done to afford freedom of movement of the cam follower 21 and to permit adjustments to be made for small variations in the initial distance between the ends 11 and 12 of the lamp. The V-blocks 9 and 10 are properly positioned on the lamp 2 when the outer faces of cam 20 and cam follower 21 respectively abut the ends 11 and 12 respectively of the lamp.

In order to prevent distortion of the cross section of the lamp 2 during the heating and flattening operation the arm 7 is provided with a support 16 which comprises a block 17 attached to the arm 7, a pin 18 extending through the block 17 and a locking screw 19. After the arm 7 has been positioned the screw 19 is loosened to permit the pin 18 to drop down in the block 17 until it touches the base plate 1. The pin 18 is then locked in this position by the locking screw 19. In this way, the V-block 9 still engages the lamp 2 but its weight and the weight of the arm 7 is now carried by the pin 18.

The lamp 2 is now ready for the flattening operation. This assembly is then placed in a heating chamber where it is exposed to heat of a degree calculated to cause the glass, of which the lamp 2 is made, to soften and become plastic. When the glass softens the weighted V-block 10 will slowly, by force of gravity, push the raised end 12 of the lamp 2 downwardly until the entire lamp rests on the base plate 1 and the ends 11 and 12 thereof are in proper circular alignment and spaced the predetermined distance.

In placing this assembly in a heating chamber it has been found desirable to elevate the side of the base plate which supports the raised end of the lamp about 8 degrees. This is done to insure a positive contact between the cam 20 and its follower 21 as the end 12 of the lamp moves into position and to make sure that when the flattening operation is completed the ends 11 and 12 of the lamp will be spaced the desired predetermined distance. This canting is particularly desirable in cases where the distance between the ends of the lamp initially is greater than the finally desired distance because, when the heated glass becomes plastic, gravity will cause the end of the lamp 12 and the cam follower 21 to move until the cam follower 21 is in contact with the cam 20. Thus the flattening operation may be satisfactorily performed on the apparatus of our invention in cases where the ends of the tube are initially spaced a greater distance from each other than the finally desired distance as well as in cases where the ends are initially closer to each other than is finally desired.

A plate 22 is mounted on top of cam follower 21. This plate serves as a means for limiting the downward movement of the weighted V-block 10 and the cam follower 21 during the flattening operation. After the end 12 of the lamp 2 has been caused to move downwardly so that the entire lamp is in contact with the base plate 1 it is extremely undesirable to have the weighted V-block 10 continued to exert pressure on the lamp. When the flattening operation has been accomplished the plate 22 will strike the top of the cam 20 on the V-block 9, thus limiting the V-block 10 from any further downward movement. Thus if the apparatus were permitted to remain in the heating chamber after the flattening of the lamp had been accomplished the plate 22 would serve as a safety device to prevent the

weighted V-block from continuing to exert pressure on the lamp and deforming the end thereof.

Referring now to the modification shown in Figures 5, 6 and 7, many of the principles embodied in the structure shown in Figures 1, 2, 3 and 4 and described above are applicable to this structure. Similar reference numerals have been used in Figures 5, 6 and 7 to designate elements which are the same as elements in Figures 1, 2, 3 and 4. The adjustable yoke 3 shown in Figure 1 has been omitted in this modification.

A lamp 2 is positioned on the instant structure in substantially the same manner in which it was positioned on the jig just described. The end 11 of the lamp is positioned so that its end surface abuts the stop 4; the lamp is centered with reference to a line running through the center of the circle which it defines and the center of the space between the ends of the lamp as finally formed; the eccentric stop is adjusted to cause it to engage the lamp; and the clamping arm is swung in to lock the lamp in position. The exhaust tube 31 is disposed on or above the stop 4.

In the present structure the V-blocks 9 and 10 are mounted on posts 23 and 24 respectively instead of on arms 7 and 8 as is done in the above-described structure. The posts 23 and 24 are mounted on the base plate 1. The V-block 10 is provided with channels 27 cut in the sides thereof, through which posts 24 extend. The weight of the V-block 9 which was removed from the lamp by the arm support 16 in the previously described apparatus is removed in the present structure by means of screw 25 which extends through the V-block 9 and a wing nut 26. After the end 11 of the lamp 2 has been positioned the V-block 9 is mounted on the posts 23 and dropped down to engage the lamp. The screw 25 is turned down until it makes a positive contact with the top of post 23. Thus the weight of the V-block 9 is carried by the posts 23 instead of the lamp 2.

In the description of the first embodiment of this invention it was pointed out that the arm 8 which carried the V-block 10 was pivotally mounted in a manner which permitted a small amount of angular movement in a horizontal plane to afford freedom of movement of the cam follower and to compensate for small variances in the initial distance between the ends of the lamp and thereby permitted the V-block 10, in all cases, to be positioned on the lamp with the outer face of the cam follower 21 abutting the end 12 thereof. In the present structure the use of cam 28 and cam follower 21 is dispensed with. Their function is now performed by the posts 24 which are not mounted perpendicular to the base plate 1 but rather at a pre-determined angle. This angular disposition of the posts 24 is calculated so that when the flattening operation is completed the stop 28, on the V-block 10, which abuts the end 12 of the lamp 2 will have caused the lamp in its plastic condition to assume a position in which the ends 11 and 12 of the lamp will be in proper circular alignment and spaced the desired distance apart.

The adjustable screw 29 mounted in the bracket 30 which is attached to the V-block 10 performs the same function as the plate 22 does in the structure illustrated in Figures 1, 2, 3 and 4, i. e., when the flattening operation has been accomplished, the screw 29 engages the top of the V-block 9 and thus shifts the weight of the V-block 10 from the end 12 of the lamp to the V-block 9. This prevents distortion of the contour of the lamp while it is plastic.

Thus the apparatus of our invention provides a means whereby one may form a substantially circular fluorescent lamp from a unit cut from a helix of glass tubing. We have found it desirable to start with a unit of tubing in which the ends are substantially parallel to a reference plane containing the axis of the helix and passing through the center of the space between the ends. We have also found it desirable to form this unit of tubing so that when the operation has been completed the ends will be in circular alignment with no point on the principal plane of either end of the tube less than a pre-determined distance from a reference plane through the center of the circle defined by the tube and perpendicular to the plane of the circle and passing through the center of the space between the ends.

However, it is to be understood that the principles herein enunciated provide the basis for the manufacturing of substantially circular electric gaseous discharge devices in which the ends are not disposed in the specific manner mentioned above without departing from the spirit of this invention. For example, it is not absolutely necessary that one start with a unit of tubing in which the ends thereof are substantially parallel to a reference plane containing the axis of the helix and passing through the center of the space between the ends. For example, one may well start with a unit of tubing in which the ends are formed from radial cuts. Similarly, it is not absolutely necessary that the ends of the tubing as finally formed be in circular alignment.

This is a division of our abandoned application Serial Number 676,193, filed June 12, 1946.

What we claim is:

1. Apparatus for forming a substantially circular glass tube in which all points on the axis of the tube are in the same plane, from a segment 40 of a helix of glass tubing, said apparatus comprising: a base member, means for positioning said tube on said base member, means for securing said tube on said base member, a pair of weighted members supported from said base member, each 45 being disposed in a position to engage the tube adjacent a free end thereof, a cam mounted on one of said weighted members, and a cam follower mounted on the other weighted member and engageable with said cam.

50 2. Apparatus for forming a substantially circular glass tube in which all points on the axis of the tube are in the same plane, from a segment 55 of a helix of glass tubing, said apparatus comprising: a base member, means for positioning said tube on said base member, means for securing said tube on said base member, a pair of weighted members supported from said base member, each 60 being disposed in a position to engage the tube adjacent a free end thereof, a cam mounted on one of said weighted members, and a cam follower mounted on the other weighted member and engageable with said cam.

65 3. Apparatus for forming a substantially circular glass tube in which all points on the axis of the tube are in the same plane, from a segment of 70 a helix of glass tubing, the ends of which are initially substantially parallel to a reference plane containing the axis of the helix and passing through the center of the space between the ends, said apparatus comprising: a base member, means for positioning said tube on said base member, means for securing said tube on said base member, a pair of weighted members supported from said base member, each being disposed in a position to engage the tube adjacent a free end there-

of, a cam mounted on one of said weighted members, and a cam follower mounted on the other weighted member and engageable with said cam.

4. Apparatus for forming a substantially circular glass tube in which all points on the axis of the tube are in the same plane, from a segment of a helix of glass tubing, said apparatus comprising: a base member, means for positioning said tube on said base member, means for securing said tube on said base member, a pair of 10 weighted members supported from said base member, each being disposed in a position to engage the tube adjacent a free end thereof, a cam

5
8
mounted on one of said weighted members, and a cam follower mounted on the other weighted member and engageable with said cam.
